UNITED STATES PATENT OFFICE.

FRIEDRICH GREINER, OF SCHWÄBISCH GMÜND, GERMANY, ASSIGNOR TO OTTO SCHLICK, OF BERLIN, GERMANY.

LUBRICATING DEVICE.

1,102,263.

Specification of Letters Patent.

Patented July 7, 1914.

Application filed August 15, 1913. Serial No. 784,950.

To all whom it may concern:

Be it known that I, FRIEDRICH GREINER, of Schwäbisch Gmünd, a subject of the King of Wurttemberg, and whose post office address is 8 Bergstrasse, Schwäbisch Gmünd, near Stuttgart, Kingdom of Wurttemberg, German Empire, have invented a new and useful Lubricating Device, of which the following is a specification.

10 This invention relates to a lubricating device provided with a gear forcing pump and adapted for use more particularly in automobiles and other vehicles and engines where such central oiling devices are used. 15 In such cases it is desirable that the device should fulfil two conditions in the working. First, it is necessary that the driving of the pump should be as simple as possible and that at the same time reciprocating 20 parts such as pistons, valves, and the like are obviated, and the second condition is that the pump should not deliver a continuous stream of oil, but that this stream should be caused to pulsate in the narrow 25 passages. The necessity for the latter requirement resides in the well known fact that the flow of liquid in narrow passages is less subject to stoppage when it is pulsating. It will be readily understood that 30 if the flow is continuous in one direction any particle of impurity which may be caught by a roughness of any kind on the interior of a tube will tend to remain where deposited and eventually, by stopping other 35 particles, cause partial or complete stoppage. If, on the other hand, the flow of liquid is pulsating, that is with a periodic back flow of the liquid, particles deposited on the interior of the passage during a 40 period of forward flow will be lifted if the current is caused to momentarily flow backward. When the direction of the current is again reversed the particle will be carried past the obstruction and similarly past any 45 other obstructions on the interior of the passage. To comply with both these conditions simultaneously is extremely difficult. Now according to the present invention this object is attained by the oil pump being constructed in a known manner as a toothed 50 gear forcing pump in which, however, according to the present invention the toothed rims of both wheels are cut out or mutilated for a corresponding distance so that 55 every time the wheels bear one on the other

at their mutilated portions the oil may find time to pass from the pressure chamber of the pump into the suction chamber whereby the desired pulsation of the oil current in the feed passages is produced 60 in spite of the simple driving and upon avoiding pistons, valves and the like. Moreover, this construction of the oil pump offers the advantage of affording a safeguard against too high a pressure in the conduits 65 and against the bursting thereof, since when the pump for some cause or other attains too high a speed whereby the pressure in the pressure conduit is increased, the pressure difference between the suction chamber and the pressure chamber is varied accordingly and the return flow of the oil from the one chamber to the other takes place to a corresponding degree through the cut-away or mutilated gear rims. 75

The drawing illustrates an improved lubricating device according to this invention, in Figure 1 in a transverse section of the pump, in Fig. 2 in a longitudinal section, and in Fig. 3 in a lateral section. 80

As shown, the bottom of an oil tank *a* is provided with a casing *b* of a toothed gear forcing pump which comprises in known manner two oppositely rotating toothed wheels *c* and *d*. Of these, one wheel 85 is driven, for instance, by a worm gear *e* *f*, so that only the driving shaft *g* projects outwardly. Arranged to communicate with the suction chamber *h* of the pump, in the cover of the pump casing, as indicated in 90 dotted lines in Fig. 2, is an opening *i* so that the oil is free to enter the pump casing directly without any intermediate conduit. Leading from the pressure chamber *k* of the pump to the individual branch conduits *m* are pressure conduits *l*. In the branch conduits *m* are arranged in a known manner the oil level indicators *n* and leading from the latter, as shown in Fig. 2, are the individual passages *o* arranged in the 95 cover of the casing and terminating in the connecting socket *p*. A needle valve *q* enables the cross-section to be regulated and a covering screw *r* is provided to guard against unauthorized manipulation. 100

As shown in Figs. 1 and 2, recesses *s* and *t* are produced in the toothed rims of the wheels *c* and *d* by cutting away the teeth to an equal distance on both wheels so that when these recesses face one another, as 110

shown in Fig. 1, during each rotation of the wheels, a direct communication is established between the suction chamber *h* and the pressure chamber *k* of the pump where-
5 by in each revolution a return flow takes place and a pulsation is brought about in the pressure conduits.

What I do claim as my invention, and desire to secure by Letters Patent of the
10 United States, is:—

1. In a gear forcing pump for lubricating systems, the combination with a casing provided with suction and pressure chambers, of gears in the casing, said gears having
15 means operative during a predetermined interval occurring in each revolution of the gears to periodically establish communication between the pressure chamber and the suction chamber.

2. In a gear forcing pump for lubricating systems, the combination with a casing provided with suction and pressure chambers, of gears in the casing, said gears having
20 means operating synchronously with the gears during a portion of the rotation thereof to establish communication between the pressure chamber and the suction chamber.

3. In a gear forcing pump for lubricating systems, the combination with a casing provided with suction and pressure chambers,

gears in the casing, the gears being cut away to provide a free passage between the suction and pressure chambers periodically, as the gears rotate.

4. In a gear forcing pump for lubricating systems, the combination with a casing provided with suction and pressure chambers, gears in the casing, equal portions of the rims of the gears being cut away to provide
35 a free passage between the suction and pressure chambers periodically, as the gears rotate.

5. In a lubricating device, the combination with an oil tank, of a gear forcing pump having its casing integral with the bottom of the said oil tank, oil passages arranged in the said bottom and connected with the pressure chamber of the said pump, a port in the said pump casing to connect
45 the oil tank with the suction chamber of the said pump and means for periodically establishing communication between the pressure chamber and the suction chamber.

In testimony whereof I have hereunto
50 set my hand in presence of two subscribing witnesses.

FRIEDRICH GREINER.
